UNITED STATES PATENT OFFICE

FLOYD S. PARMENTER, OF LOS ANGELES, CALIFORNIA

DESIGN FOR AN ELECTRIC TABLE LAMP

Application filed March 6, 1931. Serial No. 38,970. Term of patent 3½ years.

To all whom it may concern:

Be it known that I, FLOYD S. PARMENTER, a citizen of the United States, residing at Los Angeles, in the county of Los Angeles and State of California, have invented a new, original, and ornamental Design for Electric Table Lamps, of which the following is a specification, reference being had to the accompanying drawings, forming part thereof.

Fig. 1 is an elevation taken in the direction of the arrow 1 of Fig. 2.

Fig. 2 is an elevation taken in the direction of the arrow 2 of Fig. 1.

Fig. 3 is a bottom view taken in the direction of the arrow 3 of Fig. 1, this view being illustrated on a somewhat smaller scale.

Fig. 4 is a plan view taken in the direction of the arrow 4 of Fig. 1, this view being illustrated on a somewhat smaller scale.

I claim:

The ornamental design for an electric table lamp, as shown.

FLOYD S. PARMENTER.
